(57) **CLAIM**

The ornamental design for a video amplifier and cable adaptor, as shown and described.

DESCRIPTION

FIG. 1 is a perspective view of a device (a video amplifier and cable adaptor) having the inventive design. The device has a receptacle at its front end to which a first cable (not shown) can be removably attached and a terminal at its back end to which a second cable (shown in broken line view) can be attached.

FIG. 2 is a side view of the device shown in FIG. 1.

FIG. 3 is a front view of the device shown in FIG. 1.

FIG. 4 is a back view of the device shown in FIG. 1.

FIG. 5 is a top view of the device shown in FIG. 1; and, FIG. 6 is a bottom view of the device shown in FIG. 1.

The broken line environmental structure (a video cable) in FIGS. 1–6, and the broken line structure in FIGS. 1 and 2, are for illustration purposes only and form no part of the claimed design.
